UNITED STATES PATENT OFFICE.

HARRY JAMES WILTON, OF SEATTLE, WASHINGTON.

BUCKLE.

1,314,290.

Specification of Letters Patent. Patented Aug. 26, 1919.

Application filed January 4, 1919. Serial No. 269,620.

To all whom it may concern:

Be it known that I, HARRY J. WILTON, a citizen of the United States, and a resident of Seattle, in the State of Washington and 5 United States of America, have invented certain new and useful Improvements in Buckles, of which the following is a specification.

My invention is an improvement in 10 buckles, and has for its object to provide a buckle especially adapted for connecting the ends of a belt, wherein the buckle is formed of resilient material, shaped to form an open loop, one end of which is engaged by one 15 end of the belt, the other end of the loop having means for clasping the other end of the belt, and having means for limiting the movement of the said clasping means.

In the drawings:

- 20 Figure 1 is a front view of one embodiment of the invention;
Fig. 2 is an edge view;
Fig. 3 is a front view of another embodiment of the invention;
25 Fig. 4 is an edge view of the same;
Fig. 5 is a front view of another embodiment;
Fig. 6 is an edge view of the same;
Fig. 7 is a front view of another embodiment;
30 Fig. 8 is an edge view of the same;
Fig. 9 is a front view of another embodiment;
Fig. 10 is an edge view of the same;
35 Fig. 11 is a front view of another embodiment;
Fig. 12 is an edge view of the same.

In the embodiment of the invention shown in Fig. 1 the improved buckle, which is 40 formed from wire of suitable gage bent to proper form, consists of a bar 1 which is adapted for connection with one end of the belt, and arms 2 extending at an acute angle from the ends of the bar and crossing each 45 other, as shown.

Each arm 2 has connected with the free end thereof by means of a spacing member 3 an open loop 4, the said loops each consisting of a body and arms, one arm of 50 each loop being connected to the spacing member 3 and the other arm having a slide- able engagement with the adjacent arm of the other loop, the bodies of the loops being arranged outward and the openings of 55 the loops facing. The outer arm of one loop has a stop 5 at the free end thereof

and the outer arm of the other loop has an eye 6 slideable on the said arm of the first named loop and limited in its movement away from the body of the said first named 60 loop by the stop 5. The stop is formed by bending the end of the arm back upon itself, as shown.

In the embodiment of the invention shown in Fig. 3 the buckle comprises open 65 loops 7 and 8, the inner arms of the loops crossing and being connected to the arms 9 of a member, consisting of the said arms and a body 10, the body 10 being adapted for connection with one end of the belt. 70 The outermost arms of the loops 7 and 8 have eyes 11 which are mounted to slide upon the said arms, as shown, and the engagement of the eyes with each other or with the arms limits the movement of the 75 loops away from each other.

In Fig. 5 the body 12 of the buckle is U-shaped similar to that of 9—10 of Fig. 3, and the loops 13 and 14 are similar to the loops 7 and 8, being open loops, as shown, 80 and having the innermost arms crossing. The outermost arm of the loop 14 has a stop 15 and the outermost arm of the loop 13 has an eye 16 movable on the outermost arm of the loop 14. The stop 15 is formed 85 in the same manner as the stop 5 by bending the end of the outermost arm of the loop 14 backward upon itself.

In the embodiment of the invention shown in Fig. 7 the improved buckle consists of a body portion composed of a cross bar 17 and arms 18 extending outwardly from the ends of the bar, each end of the bar having an inwardly extending spacing member 19 for spacing the adjacent ends 95 of the arms 18 inwardly with respect to the ends of the bar. The loops 20 and 21 are similar to the loops just described, the loop 21 having a stop 22 while the loop 20 has an eye 23 sliding upon the outermost arm 100 of the loop 21. One end of the belt is connected with the bar 17, and it will be noticed that this bar has an outwardly bent portion at the center for limiting the swing- 105 ing movement of the buckle with respect to the belt.

In the embodiment of the invention shown in Fig. 9 the body portion 24 of the buckle consists of a body and arms, the arms extending approximately parallel for 110 a portion of their length and then diverging as shown, has connected with the outer end

of one arm a loop 25 and with the other a bar 26. The bar 26 has an eye 27 which slides on the outermost arm of the loop 25 and this loop has the free end thereof bent 5 backwardly over upon the arm in spaced relation, as shown at 28, to form a guide for the eye. This portion 28 forms with the arm a loop, whose ends limit the sliding movement of the eye 27.

10 In the embodiment of the invention shown in Fig. 11 the body of the buckle consists of a bar or body 29 and arms 30 extending laterally from the ends of the bar. The bar is adapted for connection with one 15 end of the belt, and it will be noticed that the arms 30 diverge slightly from the bar. Each arm 30 has connected therewith a loop 31 and 32, respectively, the outermost arm of the loop 32 having a stop 33, while 20 the outermost arm of the loop 31 has an eye 34 sliding on the outermost arm of the loop 32.

In each construction the buckle consists, 25 in effect, of a resilient member consisting of a body and arms extending laterally from the body, each arm having at the end remote from the body an open loop, the loops extending transversely of the plane of the buckle and opening inwardly. 30 These loops are adapted to grasp one end of the belt, the other end being connected with the body of the member. The innermost arms of the loops are arranged in crossed relation, and the outermost arms

are slidably connected and have means for 35 limiting the movement of the loops away from and toward each other, the stops limiting the movement of the loops away from each other, the engagement of the eye with the other loop limiting the movement of 40 the loops toward each other.

I claim:

1. A buckle comprising a resilient member consisting of a body and arms extending laterally from the body, each arm having at the end remote from the body an open loop, each loop extending transversely of the plane of the buckle and opening inwardly; said loops having their innermost arms arranged in crossed relation and 50 their outermost arms slidably connected, and means in connection with the said slideable connection for limiting the movement of the loops toward and from each other.

2. A buckle comprising a resilient member 55 consisting of a body and arms extending laterally from the body, each arm having at the end remote from the body an open loop, each loop extending transversely of the plane of the buckle and opening inwardly, said loops having their innermost arms arranged in crossed relation and their outermost arms slidably connected.

HARRY JAMES WILTON.
